[57] CLAIM

The ornamental design for a glass holder, substantially as shown and described.

DESCRIPTION

FIG. 1 is a front elevational view of a glass holder showing my new design, the rear being flat and unornamented;

FIG. 2 is a side elevational view taken from the right of FIG. 1, the side opposite being a mirror image thereof;

FIG. 3 is a top plan view thereof;

FIG. 4 is a bottom plan view thereof;

FIG. 5 is a sectional view taken in the direction of the arrows on line 5—5 of FIG. 1; and

FIG. 6 is a sectional view taken on line 6—6 of FIG. 1.

FIG. 1

FIG. 4
